(57) **CLAIM**

The ornamental design for a scanner housing, as shown and described.

DESCRIPTION

FIG. 1 is an environmental perspective view of a scanner housing, shown in conjunction with a materials handling vehicle;

FIG. 2 is a top plan view of the scanner housing;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

Broken lines and unshaded portions contained within broken lines are not claimed.

1 Claim, 5 Drawing Sheets
